CLAIM

The ornamental design for a water pump and sand tank assembly as shown and described.

DESCRIPTION

FIG. 1 is a top, front and right side perspective view of a first embodiment of a water pump and sand tank assembly showing our new design;

FIG. 2 is a top, rear and left side perspective view of FIG. 1;

FIG. 3 is a bottom, rear and right side perspective view of FIG. 1;

FIG. 4 is a bottom, front and left side perspective view of FIG. 1;

FIG. 5 is a front elevational view of FIG. 1;

FIG. 6 is a rear elevational view of FIG. 1;

FIG. 7 is a left side view of FIG. 1;

FIG. 8 is a right side view of FIG. 1;

FIG. 9 is a top plan view of FIG. 1;

FIG. 10 is a bottom plan view of FIG. 1;

FIG. 11 is an enlarged view of portion 11 in FIG. 1;

FIG. 12 is a top, front and right side perspective view of a second embodiment of the water pump and sand tank assembly;

FIG. 13 is a top, rear and left side perspective view of FIG. 12;

FIG. 14 is a bottom, rear and right side perspective view of FIG. 12;

FIG. 15 is a bottom, front and left side perspective view of FIG. 12;

FIG. 16 is a front elevational view of FIG. 12;

FIG. 17 is a rear elevational view of FIG. 12;

FIG. 18 is a left side view of FIG. 12;

FIG. 19 is a right side view of FIG. 12;

FIG. 20 is a top plan view of FIG. 12;

FIG. 21 is a bottom plan view of FIG. 12; and,

FIG. 22 is an enlarged view of portion 22 in FIG. 12.

The broken lines in the drawings illustrate portions of the water pump and sand tank assembly which form no part of the claimed design.
